Specification of Letters Patent.

Patented Dec. 3, 1918.

Application filed April 24, 1916. Serial No. 93,216.

To all whom it may concern:

Be it known that I, JONAS NORTHRUP, a citizen of the United States, residing at Hopedale, in the county of Worcester and State of Massachusetts, have invented certain new and useful Improvements in Feeler-Looms; and I hereby declare the following to be a full, clear, and exact description of the invention, such as will enable others skilled in the art to which it appertains to make and use the same.

The present invention relates to an improvement in feeler looms and more particularly to an improvement in thread parting mechanism for severing the outgoing and incoming filling ends.

Automatic weft replenishing looms employed in weaving the higher grades of fabrics are provided with a filling feeler mechanism by which the amount of filling on the bobbin in the active shuttle may be measured or determined, and, when the filling has been unwound or exhausted to a predetermined extent, the filling feeler mechanism acts to set in operation the weft replenishing mechanism. Such looms are known as feeler looms. As these looms are usually constructed the filling feeler mechanism is located on one side of the loom and the weft replenishing mechanism on the other side of the loom, so that critical or predetermined exhaustion of filling is indicated on one beat-up of the lay and the weft or filling replenishing operation takes place on the next beat-up of the lay. When the shuttle with its critically exhausted filling is boxed at the replenishing side of the loom, it is customary to sever the filling and extending from the fell of the cloth to the shuttle (this filling end being known as the outgoing filling end) at about the time the replenishing operation takes place; and when the shuttle with its fresh supply of filling has continued the weaving operation, it is customary to sever the filling end extending from the fell of the cloth to the hopper (this filling end being known as the incoming filling end). It sometimes happens after the determination of critical exhaustion of filling that the filling entirely unwinds from

the bobbin before the shuttle is boxed at the replenishing side of the loom, so that a short weft is laid in the shed, that is, a mispick results and consequently a blemish appears in the cloth. One object of the present invention is to prevent the occurrence of the above-described mispick by producing a thread parting mechanism of such construction that when the parting mechanism is brought into operation to sever the outgoing filling end, and the filling has become entirely exhausted after the indication of critical exhaustion and before the shuttle reaches the replenishing side of the loom, the thread parting mechanism will act to set in operation devices for stopping the loom.

It sometimes happens during the weft replenishing operation that the filling is broken, that is, a hopper misthread occurs, and the shuttle is picked to the opposite side of the loom without paying out an intact filling. Occasionally the break in the filling is at such a distance from the bobbin that when the shuttle is boxed at the filling feeler side of the loom, a few inches of weft extend into the shed and form a mispick. Another object of the present invention is to prevent the occurrence of this mispick by producing a thread parting mechanism of such construction that, when the parting mechanism is brought into operation to sever the incoming filling end and there is no incoming filling end to sever, the stopping devices will be set in operation by the thread parting mechanism to stop the loom.

A further object of the invention is to produce a thread parting mechanism having parter blades of such construction and arrangement that they coöperate with the reed dents or with a similar structure carried by the lay, to sever the outgoing and incoming filling ends. The parter blades are adapted to project through any part of the reed and to coöperate with the adjacent reed dents; consequently, the thread parting mechanism may occupy any position longitudinally relatively to the lay, with the result that the same reed may be employed for the weaving of all widths of cloth with-

in the capacity of the reed. Whatever the width of the cloth woven, the thread parting mechanism will be so positioned that the parter blades will project through the 5 reed immediately outside of the warp threads which are to form the selvage of the cloth. Inasmuch as the thread parting operation takes place only on the replenishing beat-up of the lay and on the beat-up 10 of the lay immediately following the replenishing operation, it is readily seen that the wear on the reed will be negligible. I believe I am the first to produce a thread parting mechanism having parter blades 15 adapted to project through and to coöperate with any section of the reed to perform the function of severing the filling. I am aware that hitherto thread parting mechanisms have been produced which have been 20 adapted to project through the reed either with or without the removal of the reed dents to perform the thread parting operation, but in these instances, so far as I am aware, the reed has not been used as one 25 of the parting members.

I believe I am the first to produce a thread parting mechanism of such construction that when it is brought into operation to sever the filling, and no filling is present to be 30 severed, the loom stopping devices will be acted upon by the thread parting mechanism to stop the loom.

To the accomplishment of these objects the invention resides in the improved thread 35 parting mechanism hereinafter described and particularly pointed out in the appended claims.

In the accompanying drawings illustrating the preferred form of the invention, 40 Figure 1 is a plan of a portion of the replenishing side of the loom showing the improved thread parting mechanism thereon; Fig. 2 is a sectional side elevation of the parts illustrated in Fig. 1 showing the 45 thread parting mechanism in normal or inoperative position, that is, in the position it occupies during the regular weaving operation of the loom; Fig. 3 is a similar view showing the positions of the parts of the 50 thread parting mechanism after it has operated to sever the outgoing filling end; Fig. 4 is a similar view showing the positions of the parts of the thread parting mechanism when the outgoing filling end has not 55 been caught between the parter blades and the reed; Fig. 5 is a side elevation of a portion of the parts of the thread parting mechanism showing their inter-relation when the lay is at its rear center; Fig. 6 60 is a detail showing the relative positions of the forward end of the release lever and its latch while the lay is at its rear center and the hopper arm has been moved to the right by an actuation of the change shaft; Fig. 7 65 is a detail showing the inter-relation of the

forward end of the release lever and its latch while the lay is at its rear center and the change shaft has returned the hopper arm to normal position; Fig. 8 is an enlarged section showing the construction of 70 the device for depressing the forward ends of the parter blades; and Fig. 9 is a dia-grammatic view showing the interrelation-ship of the various parts of a feeler loom embodying the features of the present in- 75 vention.

The loom to which the improved thread parting mechanism is applied may be of any usual or preferred construction. The portion of the loom illustrated in the drawings com- 80 prises a lay 10 mounted on the lay swords 11 for oscillation toward and from the breast beam 12. A rock or change shaft 13 journaled in brackets secured to the front of the breast beam extends across the front 85 of the loom, is connected at one end of the loom with the filling feeler mechanism, and is connected at the other end of the loom with the weft replenishing mechanism through a hopper arm 14. The change 90 shaft 13 with its connected mechanism con- stitute loom controlling devices. The plate 15 of the hopper, which contains the sup- 95 ply of filled bobbins, supports certain of the parts of the weft replenishing mechanism and is secured to a bracket 16 fastened to the breast beam 12. Pivoted at 17 on the hopper plate 15 is the shuttle feeler 18 which is connected with the hopper arm 14 through a link 19 and a spring 20. When the filling 100 feeler mechanism indicates critical exhaustion of filling, it operates to impart an os- cillatory movement in a clockwise direc- 105 tion to the change shaft 13 so as to swing the arm 14 to the right, viewing Fig. 2, 110 whereupon the lower end of the shuttle feeler 18 swings to the left to feel for the shuttle 22 and determine whether it is prop- 115 erly boxed for the replenishing operation. The shuttle travels across the lay on the shuttle race 23 with its rear wall against the reed dents 24 of the reed 25, by which each weft is beaten up against the fell of the cloth on the forward beat of the lay. The above-described parts operate in sub- 115 stantially the same manner as correspond- 120 ing parts on other filling feeler controlled weft replenishing looms.

The improved thread parting mechanism comprises parter blades 28, the forward or 120 filling engaging ends of which are adapted to pass between the reed dents and to project through the reed at all times whether the lay is on its rear center or on its for- 125 ward center and whether the parter blades are in operative or in inoperative position. By reason of this arrangement the reed dents serve as guides for the parter blades so that they shall not be injured during the oscillations of the lay toward and from the 130

breast beam. The rear ends of the parter blades are secured to a head 29 formed on the inner or parter blade end of an oscillatory parter rod 30 which is formed as a 5 crank shaft, of which the middle section 31 serves as a crank pin by which an oscillatory movement is imparted to the rod 30 to depress or raise the forward ends of the parter blades to bring the parter teeth 32, which 10 project downwardly toward the lay with their cutting edges toward the reed, either into operative or inoperative position respectively with relation to the filling. The outer end of the parter rod 30 is loosely 15 received in a hole in the free end of an arm 33 adjustably secured to a support 34 disposed in substantial parallelism to the parter rod 30. The support 34 is secured by a bolt and slot connection to a bracket 35, 20 in turn secured by another bolt and slot connection to a second bracket 36 fastened to the frame of the loom. By means of these bolt and slot connections the position of the parter blades 28 may be adjusted longitudinally of the lay. By moving the support 34 longitudinally the parter blades 28 may be brought into position to coöperate with any desired part of the reed according to 25 the width of the cloth being woven. The end of the rod 30 nearest the parter blades is received, not only for oscillatory movements but also for short reciprocatory movements toward and from the breast beam, in a horizontal slot formed in a boss 37 on the support 34. During the weaving 30 operation of the loom the forward ends of the parter blades are in raised position near the reed cap or upper rail 38 of the reed frame, so as to be out of the path of motion 35 of the shuttle as it is picked across the lay. The parter blades are maintained in this position during the weaving operation by the engagement of a cam surface 39 with the crank pin 31, the cam 39 serving to depress 40 the pin 31 and thereby raise the parter teeth 32 above the filling. The cam 39 is formed on the under side of a parter blade controller 40 provided at its rear end with a slot 41 which engages a pin 42, by which the 45 rear end of the controller is supported, projecting laterally from a forward extension 43 of the bracket 35. By means of this construction the blade controller may be moved toward and from the breast beam. When 50 the blade controller 40 is in normal position, as shown in Fig. 2, the forward end of the slot 41 is against the pin 42 which acts as a stop pin to limit the rearward movement of the controller, and the cam 39 presses down- 55 wardly against the crank pin 31. The blade controller 40 is moved into and held in this position by means of a tension spring 45, the forward end of which is secured to the forward end of the controller and the rear 60 end of which is secured to a pin fixed in the extension 43. The blade controller is moved toward the breast beam to release the rod 30, and permit the thread cutting teeth 32 of the parter blades to descend into operative position in front of the filling. 65 This forward movement of the blade controller is effected by the engagement of a hook 46 formed on the forward end of the controller with a bunter 47 secured to a plate 48 forming part of the shuttle box at 70 the replenishing end of the lay. The blade controller hook 46 is maintained above the path of motion of the bunter 47 during the weaving operation by the engagement of a cam slot 51, formed in and near the rear 75 end of a release lever 53 pivoted at its rear end on the pin 42, with a pin 50 projecting laterally from the blade controller. The forward end of the release lever 53 is held in raised position by a shoulder 54 formed 80 on the lower end of a latch lever 55 pivoted at 56 on a bracket 57 adjustably secured to the upper end of the hopper arm 14, so as to hold the forward end of the blade controller above the path of motion of the 85 bunter 47. A torsion spring 58 tends to swing the lower end of the latch lever 55 rearwardly toward the forward end of the release lever 53. The rearward movement of the latch lever is limited by a stop shoul- 90 der 59 which comes into engagement with the forward side of the bracket 57. 95 When the filling feeler mechanism indicates critical exhaustion of filling and the hopper arm 14 swings to the right and thereby disengages the latch lever shoulder 54 from the forward end of the release lever 53, the forward end of the release lever, 100 acted upon by gravity, descends until the stop lug 60 rests on the base of the bracket 16, as shown in Fig. 6. As the forward end of the release lever descends, the upper side of the slot 51 by pressing against the pin 50 depresses the hook 46 into the path of motion of the bunter 47, the stop lug 60 de- 105 termining the lowered position of the hook 46; whereupon as the lay moves forwardly the blade controller 40 is carried toward the breast beam, as shown in Figs. 3 and 4, thereby releasing the crank pin 31. The re- 110 lease of the crank pin 31 permits a spring-pressed slide 61, in the lower end of which the crank pin is loosely received, to raise the crank pin and thereby impart an os- 115 cillatory movement to the outer ends of the parter rod 30 so as to depress the parter teeth 32 of the parter blades toward the shuttle race. The slide 61 is received for vertical movements in a slide-way formed between a guide 62 and the extension 43. 120 The guide 62 is adjustably secured to the extension 43 by means of a screw 63. A compression spring 64 interposed between a rib 65 of the slide 61 and a part of the 125 guide 62 tends to impart an upward move- 130

ment to the slide 61. The limit of upward movement of the slide 61 and consequently the amount of downward movement of the forward ends of the parter blades, is determined by the engagement of the upper side of the rib 65 with a pin 66 secured in the extension 43.

While the hopper arm 14 was swinging to the right as a result of the indication of critical exhaustion of the filling, and while the latch shoulder 54 was moving out from under the forward end of the release lever 53, thereby permitting it to descend under the action of gravity and carry downward with it, by the pressure of the upper side of the slot 51 on the pin 50, the forward end of the blade controller 40 so as to depress the hook 46 in the path of the bunter 47, the lay was on its backward beat and the shuttle was picked to the replenishing side of the loom. The depression of the hook 46 into the path of the bunter 47 did not release the cam 39 from engagement with the crank pin 31, so that the forward ends of the parter blades 28 remained in raised position. During the next forward beat of the lay after critical exhaustion of filling, this being the replenishing beat-up of the lay, the bunter 47 engages the hook 46 of the blade controller 40 and pulls it toward the breast beam, thereby disengaging the cam 39 from the crank pin 31 and permitting the spring-pressed slide 61 to raise the crank pin 31 and oscillate the parter rod 30 to depress the teeth 32 of the parter blades toward the shuttle race and in front of the filling. It is assumed that, after critical exhaustion of filling was indicated by the filling feeler mechanism, enough filling remained on the bobbin to suffice for the pick of the shuttle to the replenishing side of the loom and that, therefore, a filling thread was laid in the shed, so that, as the lay moves forward on the replenishing beat-up, the cutting edges of the parter teeth 32 engage the filling and present it to the forwardly moving reed dents 24; whereupon, owing to the continued forward movement of the lay and of the reed dents, the filling is severed between the cutting edges of the parter teeth and the reed dents. Inasmuch as the replenishing operation is completed by the time the lay reaches its forward center, it will be observed from an inspection of Fig. 3 that the thread parting operation takes place slightly before the completion of the replenishing operation, that is, the thread parting operation takes place about the time the warps are crossing each other for the next shedding. While the lay was on its replenishing beat-up and the blade controller 40 was being carried forward owing to the engagement of the bunter 47 with the hook 46, the pin 50, carried by the controller 40, acted upon the upper side of the

cam slot 51 formed in the release lever and lifted the forward end of the release lever 53 into position to permit the latch lever shoulder 54 to swing under it, as shown in Figs. 3 and 4. At this time, however, the hopper arm 14 was still to the right. Upon the first return or backward beat of the lay after the replenishing operation and the consequent disengagement of the bunter 47 from the hook 46, the spring 45 acting upon the blade controller 40 draws the blade controller rearwardly as the lay beats back, thereby permitting the forward end of the release lever 53 to descend before the latch shoulder 54 has had opportunity to swing under it. By the time the lay has reached its rear center the hopper arm 14 has swung to the left toward the breast beam, bringing the rear side of the shoulder 54 into engagement with the forward end of the release lever, the spring 58 permitting the latch lever 55 to yield slightly, as shown in Fig. 7.

The assumption is that during the replenishing operation no mishap occurred and, consequently, on the first pick of the shuttle away from the replenishing side of the loom an intact filling was laid in the shed. On the first beat-up of the lay following the replenishing operation, the parts of the thread parting mechanism being in the same position in which they were in on the replenishing beat-up of the lay, the engagement of the bunter 47 with the hook 46 acts to release the cam 39 from the crank pin 31 to permit the slide 61 to depress the parter teeth 32 toward the shuttle race, so that they may present the filling to the forward movement of the reed dents 24. As the lay completes its forward beat, the filling is severed in the same manner as before. This forward beat of the lay resulted, as before, in the raising of the forward end of the release lever 53, whereupon the latch lever 55 under the actuation of its spring 58 swings the shoulder 54 under the forward end of the release lever, so as thereby to hold it and the forward end of the blade controller in a raised or inoperative position. All the parts of the thread parting mechanism are now in their normal or inoperative position, as shown in Fig. 2, and remain in this position until critical exhaustion of filling is again indicated by the filling feeler mechanism. It is thus seen that the outgoing filling end is severed on the replenishing beat-up of the lay and the incoming filling end is severed on the first beat-up of the lay following replenishment, and, consequently, this latter filling end is severed before it has had opportunity to break and snap into the shed. Thus, one cause of double picks, that is, the laying of two wefts in one shed, is eliminated.

If, after the determination of critical exhaustion of filling, it should happen that the filling should entirely unwind and exhaust

the bobbin before the shuttle reaches the replenishing side of the loom, a short weft would be laid in the shed causing a mispick, and so means are provided to stop the loom, 5 to permit the operator to pick out the short weft. When the parter blades 28 are depressed toward the shuttle race and they do not present any filling to the reed dents 24, the thread parting mechanism operates 10 to cause loom stoppage. The connections between the thread parting mechanism and the loom stopping devices comprise a U-shaped stop controller 69 of which the rear ends are received in collars 71 secured to a 15 pivot pin 72 journaled in the upper arm 73 of a stop lever 74 fulcrumed at 75 on the loom frame. A link 76 connects the lower arm of the stop lever 74 with the free end of an arm 77 secured to a stop shaft 78 connected with the usual means for stopping the loom. These parts constitute loom stopping devices. A compression spring 79 interposed between a lug on the loom frame and the forward side of the upper arm 73 of the 20 stop lever 74 tends to swing the upper arm of the lever 74 to the left and the lower arm of the lever 74 and arm 77 to the right, viewing Fig. 2. The extent of these movements is limited by the upper end of the stop lever 25 coming into contact with the loom frame.

On a framework 80 rising upwardly from the lay is secured an actuator 81 having a barb 82 for engaging the cross-bar 70 of the stop controller, so as thereby to actuate the 30 loom stopping devices. When the cross-bar 70 is permitted to be engaged by the barb 82 on the forward beat of the lay, the continued forward motion of the lay and of the actuator 81 draws the cross-bar 70 forward and oscillates the stop lever 74 on its pivot 75 in a clockwise direction, thereby 35 swinging the lower arm of the lever 74 to the left and through the link 76 and the arm 77, oscillating the stop shaft 78 in a clockwise direction to release the shipper or other 40 stopping means and stop the loom. The cross-bar 70 of the stop controller 69 is maintained during the weaving operation in the upper end of an obliquely disposed cam 45 slot 84 formed in a cam piece 85 secured by a bolt 86 to a lug 87 projecting upwardly from the blade controller 40. It will be observed, therefore, from an inspection of Fig. 50 2, that during the regular weaving operation of the loom the cross-bar of the stop controller 69 is above the path of motion of the barb 82 of the stop actuator 81.

Upon an oscillation of the change shaft 13, resulting from the indication of critical 55 exhaustion of filling and the consequent forward movement of the blade controller 40 and the cam piece 85, the upper side of the cam slot 84 by acting upon the cross-bar 70 causes it to descend to the mouth of the slot 60 84, in which position it is in the path of the

barb 82. By means of the cam slot 84 the cross-bar 70 is positively and rapidly moved from its inoperative position above the path of the actuator 81 into the path of the actuator. Thus the uncertainty of gravity 70 action is eliminated. At this time the barb 82 is somewhat to the rear of the cross-bar 70 and the cutting edges of the parter teeth 32 are in front of and distant from the reed dents about the thickness of a filling thread. 75 If now, there is filling between the cutting edges of the parter teeth 32 and the dents 24, this filling will be of sufficient strength, whatever its fineness, to cause the parter blades 28 to be drawn forward with the lay 80 until the parter end of the rod 30 is drawn to the forward end of the slot formed in the boss 37. As the parter end of the rod 30 moves forward it carries with it a link 89 of which the forward end embraces the crank 85 pin 31, and the rear end is loosely received in a hole in the lower end of an arm 90 depending from the pivot pin 72, whereupon check nuts 91 threaded on the free end of the link 89 pressing against the rear side of the lower 90 end of the arm 90 carry it forward and oscillate the pivot pin 72, thereby swinging the cross-bar 70 of the stop controller 69 upwardly clear of the path of motion of the barb 82. Thereupon, the lay and the stop 95 actuator complete their forward movement without affecting the loom stopping devices. If, however, no filling was caught between the cutting edges of the parter teeth and the reed dents 24, the parter end of the rod 30 would not be drawn forward, the link 89 and the arm 90 would remain quiescent, and the cross-bar 70 of the stop controller would remain in the path of the barb 82, so that, as the lay continued its forward movement, the 100 barb 82 would engage the cross-bar 70, thereby swinging the stop lever 74 about its pivot and imparting an actuation to the stop shaft 78; whereupon the loom would be stopped. Thus it is seen that if the cross-bar 105 70 of the stop controller 69 is permitted to remain in lowered position, it indicates that filling is absent and that the loom should be stopped. And conversely, if the cross-bar 70 is swung upwardly clear of the 110 barb 82, it indicates the presence of filling at the time of the thread parting operation.

In order that the forward ends of the parter blades 28 may be raised clear of the path of motion of the shuttle on the backward beat of the lay after the thread parting operation, the stop actuator 81 is provided with a cam surface 93 which, as the lay beats backward, comes into engagement with the crank pin 31 and depresses it, 115 thereby raising the forward ends of the parter blades 28 above the path of motion of the shuttle. The arrangement of these parts and the timing of their operation are such that before the shuttle passes the place 120 125 130

occupied by the parter blades, the cam shoulder 93 engages the crank pin 31 so as to lift the forward ends of the parter blades above the shuttle and then, as the lay continues its backward beat, the spring 45, acting upon the blade controller 40, brings the cam surface 39 into engagement with the crank pin 31 and, consequently, the forward ends of the parter blades are continued in their raised position during the backward beat of the lay.

It will be observed from an inspection of Fig. 2 that during the normal operation of the loom and the retention of the cross-bar 70 of the stop controller 69 in the upper end of the cam slot 84 a space separates the rear side of the lower end of the arm 90 and the check nuts 91. This space corresponds to the drop between the upper and lower ends of the cam slot 84, so that, after the actuation of the change shaft 13 and the swing of the hopper arm 14 to the right, and the consequent forward movement of the blade controller 40 and the cam piece 85, the passing of the cross-bar 70 into the mouth of the cam slot 84 serves to bring the rear side of the lower end of the arm 90 against the check nuts 91, so that the slightest force exerted upon the parter end of the rod 30 in the direction of the breast beam serves to tilt the stop controller 69 on its fulcrum. In this connection it will be observed that the stop controller 69, the link 89 and the parter rod 30 are of very light construction so that they respond readily to the slight forward movement of the parter blades 28 when the cutting edges of the parter teeth present the filling to the severing action of the reed dents 24.

In the foregoing description of the specific embodiment of the present invention, the features of the invention have been described as coöperating to sever the outgoing and incoming filling ends on a feeler controlled, weft replenishing loom, and if these filling ends are not present, to stop the loom. The thread parting mechanism has been described as being set in operation by a turning of the change shaft connected with the filling feeler mechanism. It will be understood, however, that the invention is not limited to application to feeler controlled, automatic weft replenishing looms, but is also adapted for application to other types of automatic weft replenishing looms as, for example, those which are controlled by a filling detector mechanism connected with the change shaft. In case the invention is applied to a filling detector controlled, automatic loom, the thread parting mechanism would of course be employed only to sever the incoming filling end, inasmuch as there would be no outgoing filling end. In this case the thread parting mechanism would

not be employed to stop the loom on filling absence, but the loom would be stopped through the action of the filling detector in the usual manner.

Having thus described the invention, what is claimed is:

1. A loom having, in combination, loom controlling devices, loom stopping devices, a thread parting mechanism arranged to sever the outgoing and incoming filling ends, and connections between the loom stopping devices and the thread parting mechanism operating to cause an actuation of the loom stopping devices when the thread parting mechanism is thrown into position to perform the thread severing operation, and either the outgoing filling end or the incoming filling end is not present.

2. A loom having, in combination, controlling devices, a thread parting mechanism having parter blades normally in inoperative position and adapted to be brought to operative position upon an actuation of the controlling devices, loom stopping devices, and means having provision for connecting the thread parting mechanism with the stopping devices to cause loom stoppage if there is no filling present when the parter blades are brought into operative position.

3. A loom having, in combination, loom controlling devices, a lay, loom stopping devices including a stop shaft, a thread parting mechanism, connections between the stop shaft and the thread parting mechanism comprising an actuator mounted on the lay, a stop lever, a stop controller pivoted on the stop lever adapted, when the thread parting mechanism is set in operation and there is no filling present, to be operated upon to be engaged by the actuator to act upon the stopping devices and stop the loom.

4. A loom having, in combination, loom controlling devices including a hopper arm, a thread parting mechanism comprising parter members fixed on the lay and parter blades mounted on a stationary part of the loom rearwardly of the lay adapted to co-operate with the parter members to sever the filling, and connections between the parter blades and the loom controlling devices arranged to hold the parter blades above the path of the shuttle during regular weaving, and to lower the parter blades so as to be in position to engage the filling on an operation of the loom controlling devices.

5. A loom having, in combination, weaving devices including a reed, and a thread parting mechanism, having provision for adjustment longitudinally of the reed, comprising parter blades adapted to coöperate with the reed to sever the filling at any distance from the selvage of the cloth according to the position of the parting mechanism relatively to the reed.

6. A loom having, in combination, weaving devices including a reed, and a thread parting mechanism having parter blades adapted to coöperate with the reed dents to sever the filling. 65
7. A loom having, in combination, weaving devices including a reed and a thread parting mechanism having parter blades adapted to project through the reed and to coöperate with the reed dents to sever the filling. 10
8. A loom having in combination, weaving devices including a reed, and a thread parting mechanism having parter blades adapted to project through the reed at all times during the operation of the loom and to be in raised position above the path of the shuttle during normal operation of the loom. 15
9. A loom having, in combination, weaving devices including a reed, and a thread parting mechanism comprising parter blades adapted to project through the reed, having cutting edges arranged to engage the filling and present it to the reed so that it may be severed between the cutting edges and the reed dents. 20
10. A weft replenishing loom having, in combination, weft replenishing mechanism, thread parting mechanism on the weft replenishing side of the loom, stopping devices, and connections between the weft replenishing mechanism, the thread parting mechanism and the stopping devices operating upon an actuation of the weft replenishing mechanism to sever the filling if it be present, and to stop the loom if the filling be absent. 30
11. A weft replenishing loom having, in combination, weft replenishing mechanism, thread parting mechanism located on the weft replenishing side of the loom, stopping devices, and connections between them, the weft replenishing mechanism, the thread parting mechanism, and the stopping devices coöperating to cut the outgoing filling end if it be present, and to stop the loom if it be absent. 40
12. A weft replenishing loom having, in combination, weft replenishing mechanism, thread parting mechanism located on the weft replenishing side of the loom, stopping devices, and connections between them, the weft replenishing mechanism, the thread parting mechanism, and the stopping devices coöperating to cut the incoming filling end if it be present, and to stop the loom if it be absent. 50
13. A weft replenishing loom having, in combination, weft replenishing mechanism, thread parting mechanism located on the weft replenishing side of the loom, stopping devices, and connections between them, the weft replenishing mechanism, the thread parting mechanism, and the stopping devices coöperating to cut the outgoing and incoming filling ends if they be present, and to stop the loom if they be absent. 60
- parting mechanism, and the stopping devices coöperating to cut the outgoing and incoming filling ends if they be present, and to stop the loom if they be absent. 65
14. A feeler loom having, in combination, weft replenishing mechanism, filling feeler mechanism, loom controlling devices, stopping devices, thread parting mechanism on the weft replenishing side of the loom, and a filling detector mechanism on the side of the loom remote from the weft replenishing mechanism, said devices and mechanism being operatively interconnected, the filling detector mechanism acting to cause loom stoppage when it detects filling absence, and the thread parting mechanism acting to cause loom stoppage if filling is absent on the weft replenishing beat or on the succeeding beat-up of the lay. 70
15. A feeler loom having, in combination, weft replenishing mechanism, filling feeler mechanism, loom controlling devices, thread parting mechanism on the weft replenishing side of the loom, stopping devices, means operatively connecting the thread parting mechanism with the loom controlling devices and the stopping devices, and a filling detector on the side of the loom remote from the weft replenishing mechanism operating to cause loom stoppage upon absence of filling, said parting mechanism operating upon weft replenishment to sever the outgoing and incoming filling ends and to cause loom stoppage if the outgoing and incoming filling ends are absent. 80
16. A loom having, in combination, loom controlling devices, stopping devices, a thread parting mechanism, and means connecting the parting mechanism with the loom controlling devices and the stopping devices, said parting mechanism remaining in inoperative condition until an actuation of the controlling devices, whereupon it operates to cause an actuation of the stopping devices to stop the loom if filling is absent. 90
17. A loom having, in combination, loom controlling devices, stopping devices, a thread parting mechanism, and connections between the stopping devices and the thread parting mechanism including a stop actuator, a stop controller and means for holding the stop controller disconnected from the stop actuator during normal weaving, said means having provision for positively moving the stop controller into a position to be engaged by the stop actuator upon an actuation of the loom controlling devices. 100
18. A loom having, in combination, loom controlling devices, stopping devices, a thread parting mechanism, and connections between the stopping devices and the thread parting mechanism including a stop actuator, a stop controller and means for holding the stop controller disconnected from 110

the stop actuator during normal weaving, said means having provision for positively moving the stop controller into a position to be engaged by the stop actuator upon an actuation of the loom controlling devices, said thread parting mechanism having provision for permitting and for preventing engagement of the stop controller by the stop actuator according to whether outgoing or incoming filling ends are absent or present.

19. A loom having, in combination, weaving devices including a lay, and a thread parting mechanism comprising parter members fixed uprightly on the lay, a shaft journaled on a stationary part of the loom rearwardly of the lay, parter blades mounted at their rear ends on the shaft, and means for oscillating the shaft to move the forward ends of the blades into and out of filling ends gaging position.

20. A loom having, in combination, weaving devices, a reciprocatory member, a filling engaging member, loom stopping means, a stop controller, connections between the filling engaging member, the loom stopping means, and the stop controller having provision for moving the stop controller out of the path of the reciprocatory member when an intact filling is presented to the filling engaging member, and for permitting the stop controller to be engaged by the reciprocatory member to actuate the stopping means when no filling is presented to the filling engaging member, and means to hold the stop controller out of the path of the reciprocatory member during regular weaving, and to move it into the path of the reciprocatory member upon a change in the operation of the loom.

40 21. A feeler loom having, in combination, a reed, filling feeler mechanism, weft replenishing mechanism, loom controlling devices connecting the two mechanisms, a thread parting mechanism having parter blades adapted to coöperate with the reed to sever the filling, and means for controlling the operation of the parter blades having provision for holding them in inoperative position during normal weaving and for throwing them into operative position on the indication of critical exhaustion of filling by the filling feeler mechanism, for raising them to inoperative position on the first return beat of the lay after the replen-

ishing operation, for returning them into operative position before the next forward beat of the lay, and for returning them into inoperative position during the next succeeding return beat of the lay.

22. A feeler loom having, in combination, 60 a reed, filling feeler mechanism, weft replenishing mechanism, loom controlling devices connecting the two mechanisms, and a thread parting mechanism comprising parter blades adapted to coöperate with the reed to 65 sever the filling, said parter blades being arranged so that their thread severing ends project through the reed continuously during the loom operation, and having a normal position above the path of the shuttle, means 70 for lowering the parter blades into operative position during the weft replenishing beat-up of the lay and on the succeeding beat-up of the lay, means for raising the parter blades into inoperative position between the 75 said two beats-up of the lay, and means for holding the parter blades in their normal position during regular weaving.

23. A loom having, in combination, weaving devices including a lay, parter members 80 fixed on the lay, and a thread parting mechanism having movable parter members located rearwardly of the lay on a stationary part of the loom, adapted to coöperate with the lay parter members to sever the filling. 85

24. A loom having, in combination, weaving devices including a lay, parter members fixed on the lay, and a thread parting mechanism comprising movable parter blades mounted on a stationary part of the loom 90 rearwardly of the lay, said parter blades being adapted to engage the filling and hold it in the path of the forwardly moving parter members on the lay.

25. A loom having, in combination, loom 95 controlling devices including a hopper arm, and a thread parting mechanism comprising parter members fixed on the lay, parter blades mounted on a stationary part of the loom rearwardly of the lay, and connections 100 between the parter blades and the hopper arm comprising a controller for normally holding the blades out of filling engaging position, and means for moving the controller to permit the blades to be moved into 105 filling engaging position.

JONAS NORTHRUP.
